HINGE ASSEMBLY FOR A SWINGABLE DOOR
Russell N. Carey, Niles, Mich., assignor to Eliason Re-
frigerator Company, Hartford, Mich., a corporation of
Michigan

Filed Feb. 7, 1963, Ser. No. 256,848
14 Claims. (Cl. 16—154)

This invention relates in general to a hinge construction for supporting a swingable door and, more particularly, to a type of hinge construction which mildly resists movement of the door away from a selected "at rest" position and utilizes gravity to return said door gently to said "at rest" position.

Swinging doors of the self-closing type, which include those doors referred to as gravitating doors, are well known in the art and have been used for many years. However, doors of this general character have not, insofar as I am aware, been capable of fully satisfactory operation in certain types of installations, particularly where problems of heat transfer are encountered.

Existing self-closing doors are frequently equipped with spring actuated hinges or steeply inclined cams which produce a rapid return to the "at rest" position and strongly resist opening. The tendency for a rapid return greatly increases the possibilities for damage to the door and injury to personnel using the same. Moreover, the fast return causes the door to interfere with the movement of personnel and equipment through the opening in which the door is hung.

However, if the spring mechanism is weakened, or if the slope of the cam mechanism is reduced, in order to slow down the return movement of the door toward its closed or "at rest" position then the operation of the door often becomes sluggish and ineffective. That is, minor obstructions, such as a dragging gasket on the edge of the door, can prevent proper return movement of the door to its fully closed position. Moreover, the return urging of the door may be so reduced that it will be incapable of overcoming the friction and inertia of the door so that it will remain open.

Where steep cams are used, primarily because they are required to overcome the initial resistance and inertia of the door, it is often necessary to provide special edge structures on the upper and lower edges of the door to compensate for the upward and downward movement of the door while it is opening or closing.

Many self-closing, swinging doors, which are supported by existing hinge construction, become misaligned after a relatively short period of normal usage. That is, the door does not accurately return to a fully closed position when it is "at rest," even though it is not materially obstructed in its return movement.

Aside from the bad appearance of a misaligned door, or the time and expense required to keep it aligned, there is the further problem of the heat loss which occurs where such doors are used in the entry to a cold storage room. Since the problems that arise from a poorly fitting or poorly operating swinging door are more serious where the door is used in the entrance to a cold storage room, reference is made herein to such use for illustrative purposes. However, the applicant's hinge construction is capable of improving the operation of double acting, swinging doors of the self-closing type, regardless of the specific utilization. For example, the applicant's hinge construction can be used to support a door for an opening in a partition wall.

Applicant's improved hinge construction causes the door which it supports to develop a pendulous action as it swings from its substantially fully open position into its substantially closed position. Thus, when the door is moved into a substantially open position, it tends to dwell

2

in said open position until gravity overcomes inertia and initiates the return movement.

Accordingly, the objects of this invention have been:

(1) To provide an improved hinge construction for a swinging door of the self-closing type, which construction is relatively inexpensive to manufacture, easy to install on door panels having a wide variety of sizes and shapes, easy to mount upon wall structures defining existing openings or easy to install as an integral part of the wall construction as it is being built, and pleasing in appearance.

(2) To provide a hinge construction, as aforesaid, which can be substantially hidden from view, which can be easily and initially adjusted so that it will repeatedly return the door to a predetermined, "at rest" position in a gentle manner and in response to the force of gravity, only, and which can be operated repeatedly over long periods of time without necessitating readjustment of the hinge construction in order to return the door to its "at rest" position.

(3) To provide a hinge construction, as aforesaid, which permits the use of sealing gaskets along the edge of the door to minimize heat transfer through the opening in which the door is located, which permits double acting swinging movement of the door either by itself or in cooperation with another swinging door in the same opening supported by a similar hinge construction, and which is arranged so that the swinging door tends to move from its open position to its closed position with a slow, pendulous movement which is easily damped when and as the door reaches its "at rest" position by damping mechanism integral with the hinge construction.

(4) To provide a hinge construction, as aforesaid, which permits opening of the door supported thereby with a minimum of force applied to the door in a horizontal direction, which requires little or no maintenance, such as periodic lubrication which attracts dust and dirt to the lubricated parts, and which can operate effectively without return springs or steep cam surfaces to effect the return movement of the door toward its "at rest" position.

Other objects and purposes of this invention will become apparent to persons familiar with this type of equipment upon reading the following descriptive material and examining the accompanying drawings in which:

For convenience in description, the terms "upper," "lower" and words of similar import will have reference to the hinge construction of the invention and a door associated therewith as appearing in FIGURES 1, 9 and 12. The terms "inner," "outer" and words of similar import will have reference to the geometric center of said hinge construction, units thereof and parts associated therewith.

General Construction

The objects and purposes of the invention, including those set forth above, have been met by providing an improved hinge construction for supporting a swingable door for substantially horizontal movement in either direction away from an "at rest" position into which said door is gently urged entirely by gravity. The hinge construction is comprised of an upper hinge unit, which controls the gravitating movement of the door, and a lower hinge unit which guides such movement. The hinge axis is disposed at an angle to and adjacent to one vertical edge of the door, such angle diverging upwardly and being disposed within the door opening. The hinge construction of the invention can be built into the wall surrounding the opening with which it is associated, or it may be installed within the opening after the wall structure is completed.

Detailed Description

The hinge construction (FIGURES 1 and 2), which has been selected to illustrate the preferred embodiment of the invention, is comprised of an upper hinge 10 and a lower hinge 11 which pivotally connect the upper and lower parts, respectively, of the door 12 to the adjacent portions of the wall 13 defining the opening 14 in said wall. For illustrative purposes, a second door 16 is mounted by means of the upper hinge 17 and lower hinge 18 upon the wall 13 within the opening 14 so that the doors 12 and 16 substantially completely close the opening 14 when said doors are in their "at rest" positions, as appearing in FIGURE 1. The door 16, upper hinge 17 and lower hinge 18 are preferably, but not necessarily, identical with the door 12, upper hinge 10 and lower hinge 11, respectively. Accordingly, a detailed description of the door 12 and its hinges 10 and 11 will be given hereinafter and such description will be understood to apply, at least in substance, to the door 16 and its hinges 17 and 18.

The door 12 (FIGURE 1) may be of a substantially conventional type which, in this particular embodiment, may be fabricated from a substantially rigid and durable material such as wood, plastic and/or metal. Where the door is fabricated from a light weight, easily marred material, such as wood or aluminum, it is at least desirable to provide more durable surface panels 19 and 20 to absorb the rough treatment given to such doors, particularly when they are opened by means other than hands. That is, swinging doors of the type for which the hinges 10 and 11 are specifically designed, are frequently opened by vehicles, containers or the like which are moved through the opening in which the door is supported. The lower panel 20, which would normally receive the rougher treatment, may advantageously be fabricated from somewhat heavier material than the material required in the upper panel 19. The added weight

in said lower panel 20 also facilitates the closing movement of the door as discussed hereinafter.

The opening 14 in the wall 13 is defined by a threshold 22 on the floor 23 a head jamb 24 and a pair of side jambs 26 and 27 which extend between said threshold 22 and said head jamb 24. In this particular embodiment, the head jamb 24 and side jambs 26 and 27 are disclosed as channel-shaped members which slidably embrace adjacent portions of the wall 13. The head jamb 24 (FIGURE 4) is held in place by means such as bolts 28, and said side jambs 26 and 27 are held in place by means such as the bolts or screws 29 and 30, respectively (FIGURE 2). The head jamb 24 and side jambs 26 and 27 (FIGURES 3 and 5) may be rigidly connected to each other near their adjacent ends by means such as the bolts 33.

The upper hinge 10 includes a pivot member 34 (FIGURES 3, 6 and 7), which is connected to the upper end of the door 12, and a support member 36 which is secured to and within the head jamb 24. More specifically, pivot member 34 (FIGURE 3) includes a mounting plate 37, which is rigidly secured to the door 12 by screws 38. The mounting plate 37 (FIGURES 4 and 7) has an integral, sidewardly extending flange 39 at its upper end to which an upwardly extending pivot pin 42 is rigidly secured, as by welding. The pivot axis 50 (FIGURE 1) of the pivot pin 42 is preferably parallel with the lengthwise extent of the mounting plate 37.

A roller shaft 43 (FIGURE 5) extends through and is snugly held within a diametrical opening 44 through the pivot pin 42, preferably so that said shaft 43 is perpendicular to the plane defined by the mounting plate 37. A pair of rollers 46 and 47 are rotatably supported upon the shaft 43 on opposite sides of the pivot pin 42 and are held upon said shaft 43 by means such as the spring clips 48 and 49. The rollers 46 and 47 are preferably identical in size and shape and are also preferably fabricated from a durable, self-lubricating material, such as nylon. However, said rollers 46 and 47 could also be made of hardened steel, or they could be roller or ball bearings.

The pivot member 34 (FIGURE 3) is preferably mounted upon the door 12 so that the axis 50 of the pivot pin 42 is inclined with respect to the adjacent side jamb 27 at an angle of approximately 3°, when the door 12 is in its "at rest" position within the opening 14, which position is substantially parallel with the wall 13. In said "at rest" position, the roller shaft 43 is substantially perpendicular to said wall 13.

The support member 36 includes an elongated support bracket 52 which is mounted within the head jamb 24 (FIGURE 4) upon the web 51 of the channel member 53 by the bolts 54. Said channel member 53 may be welded to the head jamb 24. Said support bracket 52 has at its opposite ends a pair of integral, downwardly extending hangers 56 and 57 with integral flanges 58 and 59, respectively, which extend toward each other substantially within the same plane from the lower ends of said hangers. The plane defined by said flanges 58 and 59 is preferably disposed at an angle of approximately 3° to the horizontal, or to the web 62 of the head jamb 24 (FIGURES 3 and 6) so that said plane is substantially perpendicular to the axis 50 of the pivot pin 42.

An elongated substantially rectangular support plate 63 (FIGURES 5 and 7) is mounted upon and between the flanges 58 and 59, as by the bolts 64 and 65, which extend through openings 67 and 68 in the plate 63 and openings 69 and 70 in the flanges 58 and 59, respectively. The openings 69 and 70 in the flanges 58 and 59 are preferably elongated laterally of the bracket 52 to permit lateral adjustment of the support plate 63 with respect to the support bracket 52 when the door 12 is initially hung or later aligned within the opening 14.

The support plate 63 has a transverse upwardly opening groove 73 which is substantially V-shaped in cross

section and into which the rollers 46 and 47 are simultaneously receivable. Said support plate 63 also has a central opening 74 which preferably extends through the center of the groove 73. Said opening 74 is slightly larger than the diameter of the pivot pin 42, and said opening is located so that the pivot pin 42 does not engage the edge of the opening 74, particularly in a direction crosswise of said groove 73, when the rollers 46 and 47 are snugly disposed within the groove 73. Accordingly, the rollers 46 and 47 will always return to their fully seated positions within the groove 73 when the door is released to swing freely. The groove 73 is preferably narrow, in this particular embodiment, so that the door must be at an angle of preferably less than 45° to the "at rest" position before the rollers start to move downwardly into the groove 73. Thus, the door 12 can be swung substantially beyond its "at rest" position, as indicated by broken lines at 12a in FIGURE 5, without being held open by said groove and rollers. On the other hand, by widening the groove 73, as shown in FIGURE 5, it is possible to use said groove not only to hold the door 12 in its "at rest" or closed position, but also to hold it in an open position substantially beyond a 90° angle from its closed position.

The lower hinge 11 (FIGURES 3 and 8) includes a pivot member 78, which is mounted upon the lower end of the side jamb 27 adjacent the threshold 22 of the opening 14, and a guide member 79, which is rigidly secured to the lower end of the door 12. The pivot member 78 includes a support plate 82 which is rigidly secured near one end to the side jamb 27 and which has near its other end an upstanding pivot pin 83, which pin is preferably coaxial with the pivot pin 42, when the door 12 is in its FIGURE 1 position. The guide member 79 has a mounting plate 84, which is rigidly secured to the lower end of the door 12 by screws 86, and it has an integral sidewardly extending flange 87 at its lower end which extends under the door 12. The flange 87 has a pivot opening 88 through which the pivot pin 83 is slidably and rotatably receivable. The lower end of the door 12 may be recessed at 91 to loosely receive the upper end of the pivot pin 83.

The lower hinge 11 (FIGURE 8) is intentionally constructed so that it does not support any of the weight of the door 12, since that would interfere with the gravitational action effected by the upper hinge 10. Although the common axis 50 of the pivot pin 42 and 83 is preferably disposed at an angle of approximately 3° with respect to the adjacent edge 93 of the door 12, hence the adjacent vertical surface of the side jamb 27, other angles of inclination can be used if desired or required. For example, the inclination will effect the movement of the door from its open to its closed position and the amount of force required to move the door from its closed to its open position.

The door 12, where used to close an entry to a cold storage room, may be provided with gaskets or sealing elements 95, 95a and 96, 96a along its vertical edges 97 and 93 and its horizontal edges 98, 98a, respectively. The seals 95, 95a, 96 and 96a are preferably fabricated from resiliently flexible material, such as re-enforced rubber or plastic material, which is capable of repeated bending and rubbing with a minimum of set and/or wear. The bottom seal 96 is arranged so that it is closely adjacent the floor 23 when the door 12 is in its "at rest" position of FIGURE 1. The vertical seal 95 is arranged so that it extends slightly beyond the midway line between the adjacent edges 97 and 103 of said doors 12 and 16, respectively, when they are both in their "at rest" positions of FIGURES 1 and 2. Thus, the seal 95 will overlap and gently engage the corresponding seal 102 on the vertical edge 103 of the door 16 when it is mounted by its hinges 17 and 18 within the opening 14, as described above with respect to the door 12 and its hinges 10 and 11.

The vertical seal 95a is secured to and extends from the edge 93 of the door 12 so that said seal slightly engages the adjacent surface of the side jamb 27 when said door is in its "at rest" position. The top seal 96a (FIGURE 1), which is secured to the upper edge of the door 12, may be spaced downwardly slightly from the head jamb 24 when said door 12 is in its "at rest" position in FIGURE 1. Thus, when the door is raised slightly, as it is swung away from said "at rest" position, due to the action between the rollers 46, 47 and the support plate 63, said top seal 96a will not be jammed against the head jamb 24.

Operation

As indicated above, the doors 12 and 16 (FIGURES 1 and 2) are disposed in their "at rest" positions when their meeting edge seals 95 and 102, respectively, are in slightly overlapped engagement substantially throughout their lengths. As shown with respect to the door 12, the "at rest" position is achieved and maintained by the snug reception of the rollers 46 and 47 within the groove 73 in the support plate 63 (FIGURE 7). When the door 12 is moved around the pivot axis 50 (FIGURE 1) in one direction or the other (FIGURE 6) away from the "at rest" position, the rollers 46 and 47 are caused to climb up the side walls of the groove 73, thereby raising the door 12 slightly due to a camming action. The walls of the groove 73 are preferably relatively steep so that the rollers promptly move up onto the upper surface of the support plate 63 into their raised positions, which are indicated in broken lines at 46a and 47a in FIGURE 6. This upward movement serves the purpose of moving the bottom seal 96 away from the floor 23 with a minimum of dragging action therebetween. The groove 73 is preferably designed so that the rollers 46 and 47 do not move back into the groove 73 until the door 12 is at an angle of less than 45° to its "at rest" or its closed position. Thus, the door 12 can be moved easily into the open position, indicated by broken lines at 12a in FIGURE 5, and it can still return by gravity to its "at rest" position.

If the door 12 is unobstructed when it has reached its open position 12a (FIGURE 5), gravity will move the door 12 back toward its "at rest" position due to the inclination in the pivot axis 50 of the door hinges 10 and 11 and the cooperating, inclined upper surface of the support plate 63. This movement is largely pendulous in nature and is not intended to be a camming action. Camming occurs only after the rollers reach the groove 73 and start to move downwardly thereinto, whereby closing movement of the door tends to be accelerated slightly. However, when the rollers pass their "at rest" positions in the groove 73 continued movement of the door requires a raising thereof which immediately retards such movement. The resultant oscillation of the door 12 is quickly stopped with applicant's invention, unless the groove 73 is relatively shallow.

Because the rollers 46 and 47 (FIGURES 4 and 5) are disposed on opposite sides of the pivot pin 42, extremely accurate positioning of the "at rest" position of the door 12 can be achieved. That is, with said rollers in the groove 73, the bolts 64 and 65 are loosened so that the support plate 63 can be adjusted with respect to the flanges 58 and 59. When adjustment of the door 12 is exactly as desired, the bolts 64 and 65 are tightened. The protection panels 19 and 20 tend to shift the center of gravity of the door 12 toward the meeting edge 97 thereof, which improves the closing operation of the door, particularly on lightweight doors.

The door 12, and in a similar manner the door 16, can be quickly and easily removed for inspection and/or repair merely by removing the bolts 64 and 65 and thereafter sliding the support plate 63 sidewardly and downwardly through the opening 104 in the web 62 of the head jamb 24. Thereafter, the door 12 may be tilted and then raised so that the guide member 79 is moved away

from and off of the pivot pin 83. Alternatively, and where expedience dictates, the door 12 can be removed from its opening 14 by loosening the screws 38 which secure the mounting plate 37 to said door 12 after which the door is raised until the guide member 79 is released from engagement with the pivot member 78. Obviously, the door 12 can be quickly returned to its operating position by reversing the foregoing steps.

Modified Construction

The modified hinge construction disclosed in FIGURES 9, 10 and 11 includes an upper hinge 110 (FIGURE 9), which is connected to the upper end of the door 111, and a lower hinge 112 which is connected to the lower end of the door 111. The upper hinge 110 includes a substantially vertical hinge pin 113 which is secured at its upper end to the upper pin plate 114. The lower hinge 112 includes a lower hinge pin 116 which is secured to the lower pin plate 117. The upper and lower pin plates 114 and 117 are integral with and extend sidewardly in the same direction from the opposite ends of the jamb plate 118, which is secured by means such as the bolts 119 to the web 122 of the channel-shaped side jamb 123. The pin plates 114 and 117 are held snugly against the head jamb 124 and floor 126, respectively, which combine with the side jamb 123 to define a door opening 127 in the wall 128.

The upper hinge 110 includes a support member 131 having a support bracket 132 and support plate 133 which in general may be similar to the support bracket 52 and support plate 53 (FIGURE 3), except that their positions are reversed and inverted. A mounting plate 134 is secured to the support bracket 132 for the purpose of connecting the support member 131 by means of the screws 136 to the door 111. The upper edge of the door 111 is provided with a notch 137 into which the support bracket 132 is snugly received when said connection is accomplished.

Rollers 138 and 139 are rotatably supported upon a shaft 140 which is in turn secured to the upper hinge pin 113 in substantially the same manner as the shaft 43 is mounted upon the pivot pin 42. The support plate 133 has a central opening 142 for loose reception of the pin 113 therethrough. Said plate 133 also has a downwardly facing groove 143 which extends through the opening 142 and is engaged by the rollers 138 and 139, as discussed above with respect to the upper hinge 10, except that the corresponding elements are in the reverse positions. That is, when the door 111 is swung away from its "at rest" position in FIGURE 9, the support plate 133 moves with the door and with respect to the hinge pin 113 so that the lower surface of the support plate 133 moves upwardly onto the rollers 138 and 139, whereby the door 111 is raised slightly. A typical cover plate 144 (FIGURES 9 and 10) is mounted upon the support bracket 132 and extends across the front surface of the parts disposed therein. A similar cover plate can be mounted upon the opposite side of the support bracket 132.

The lower hinge 112 includes a guide member 146 having a mounting plate 147 which is secured by the screws 148 to the lower portion of the door 111. The guide member 146 has at its lower end a sidewardly extending flange 149 with an opening 152 through which the lower hinge pin 116 is slidably received.

The vertical jamb plate 118 is somewhat further from the upper hinge pin 113 than it is from the lower hinge pin 116 so that the hinge axis 153, which extends from the center of the opening 152 to the center of the opening 142 in the plate 133, diverges upwardly with respect to the adjacent edge 154 of the door 111. Thus, when the door 111 is moved in a substantially horizontal direction either way from its "at rest" position of FIGURE 9, gravity urges the return of the door toward its "at rest" position. The reception of the rollers 138 and 139 into the groove 143 dampens the oscillations of the door as it

swings back with a pendulous motion toward its "at rest" position and positively locates such "at rest" position.

By a minor obvious modification of the support member 131, the support bracket 132 thereof can be fabricated like the support bracket 52 (FIGURE 3) so that the support plate 133 is held in a position substantially perpendicular to the hinge axis 153 (FIGURE 9). Under such circumstances, particularly where a relatively light door is involved, it might be advantageous to tilt the hinge pins 113 and 116 so that they are coaxial with the hinge axis 153, as in the case of the hinge construction disclosed in FIGURE 3. It will be seen that the hinge construction in FIGURE 9 can be mounted to support an existing door in an existing door jamb without any material modification in either part except for the notch in the upper edge of the door 111.

The upper hinge 110 (FIGURE 9) and the upper hinge 10 (FIGURE 3) require no lubrication due to the material used in the rollers 138, 139 and 46, 47, respectively. Lubrication of the lower hinges 112 and 11, should the need become apparent, can be eliminated by providing a nylon bearing as indicated at 156 (FIGURE 11) in the flange 149 around the hinge pin 116.

The modified hinge construction, which is disclosed in FIGURES 12, 13 and 14, is adapted to support light weight, partition doors used in normal temperature installations. This construction includes an upper hinge 160 (FIGURES 12 and 13), which is connected to the upper end of the door 161, and a lower hinge 162 (FIGURES 12 and 14), which is connected to the lower end of said door 161. Broadly speaking, the upper and lower hinges 160 and 162 are similar in construction and operation to the upper and lower hinges 110 and 112, respectively, which are shown in FIGURE 9.

More specifically, the upper hinge 160 (FIGURE 13) includes an upper pin plate 164 which supports a substantially vertical hinge pin 163 and which is secured to the upper jamb 166 by screws 167. The upper jamb 166, side jamb 168 and the threshold 169 combine to define a door opening 172 in which the door 161 is swingably supported by the hinges 160 and 162. The upper hinge 160 also includes a support bracket 173 having a U-shaped mounting plate 174 which is rigidly secured to said door 161 adjacent the upper edge thereof and near one side edge 176 thereof by means of the screws 177. The upper edge of the door 161 has a recess 178 which conforms substantially exactly with the notch 179 in the mounting plate 174.

The support bracket 173 includes a pair of preferably parallel flanges 181 and 182 which are integral with, and extend in opposite directions perpendicularly from, the upper ends of the legs 183 and 184, respectively, of the mounting plate 174.

The upper hinge 160 (FIGURE 13) includes a substantially flat and elongated support plate 186 having notches 187 and 188 in diagonally opposite corners thereof, which notches form the projections 191 and 192. Said projections 191 and 192 are arranged so that they can be moved into position by rotation of plate 186, beneath the flanges 181 and 182, respectively, to engage and support the support bracket 173, hence the door 161 secured thereto. The projections 191 and 192 have bolt openings 193 and 194, respectively, which are alignable with bolt openings 196 and 197 in the flanges 181 and 182. Said bolt openings 196 and 197 are elongated in a direction substantially perpendicular to the mounting plate 174 to allow for lateral adjustment of the support plate 186 with respect to the support bracket 173 and thereby adjust the closed or "at rest" position of the free edge of the door.

The support plate 186 (FIGURE 13) has a central opening 198 into which the upper hinge pin 163 is loosely received. Said support plate 186 also has a downwardly facing groove 201 which extends diametrically through the central opening 198 and transversely of said support plate. A pair of rollers 202 and 203 are rotatably sup-

ported upon diametrically opposite sides of the hinge pin 163 by means of the roller shaft 204 which preferably extends diametrically through the hinge pin 163. The rollers 202 and 203 are arranged so that they are simultaneously and snugly receivable into the groove 201 when the pin 163 is disposed in the opening 198 and spaced from the edge thereof, at least in a direction crosswise of the groove 201. The support plate 186 can be quickly and easily disengaged from the support bracket 173 by loosening the bolts 206 and 207, which extend through the bolt openings 193, 194 and 196, 197, and then rotating the support plate 186 around the hinge pin 163 and with respect to the support bracket 173. Re-engagement is effected by reversing these steps.

The lower hinge 162 (FIGURES 12 and 14) includes a hinge bracket 211 which is secured by screws 212 to the side jamb 168 adjacent the threshold 169 and which has a hinge pin 210 extending upwardly therefrom. The lower end of the door 161 is provided with an upwardly extending recess 213 into which the lower hinge pin 210 is loosely receivable. A pair of pivot brackets 215 and 216 are rigidly secured to the opposite sides of the door 161 adjacent the recess 213 by means of nuts and bolts 217, which extend completely through the pivot brackets 215, 216 and the door 161 (FIGURE 14). The pivot brackets 215 and 216 have inwardly opening, vertical grooves 218 and 219 which open toward each other and substantially surround the recess 213 to form with said recess 213 a vertical passageway into which the hinge pin 210 is loosely received.

The side edge 176 of the door 161 is substantially closer to the recess 213 than to the center of the recess 178. Thus, the hinge axis 222 between the upper hinge 160 and the lower hinge 162 diverges upwardly with respect to the side edge 176, for substantially the same purposes as set forth above with respect to the hinge structure appearing in FIGURE 9. That is, the divergent hinge axis 222 causes the door 161 to remain in and return to an "at rest" position, which is shown in FIGURE 12, wherein the rollers 202 and 203 are snugly disposed within the groove 201. On the other hand, engagement of the rollers with the side walls of said groove 201 tends to resist movement of the door 161 away from its "at rest" position.

Aside from the specific assembly of the upper and lower hinges 160 and 162, their operation may be substantially identical to the operation of the upper and lower hinges 110 and 112, respectively, as described above. Moreover, the hinges 160 and 162 can be quickly and easily mounted within an established door opening with a minimum of effort and without special tools.

FIGURES 15 and 16 illustrate an upper hinge 230 which is a modification of the upper hinge 10 appearing in FIGURE 3. Specifically, said upper hinge 230 is comprised of a pair of spaced and similar, L-shaped support brackets 231 and 232 which may be secured to a face plate 233 secured to one side of and extending downwardly from the head jamb 234. Such securing may be effected by nuts and bolts 236, or the like. The other face plate 237 has an access opening 238 through which the support plate 239 and the upper end of the pivot member 242 can be moved sidewardly to remove the door 253 from its hinged position. The opening 238 in the face plate 237 is covered by a cover plate 243.

The support plate 239 (FIGURE 15) is provided with an upwardly facing, transverse groove 244 and a central opening 246 (FIGURE 16) in substantially the same manner as discussed above with respect to the support plate 65 63 (FIGURE 3).

The pivot member 242 includes a pin 247 (FIGURE 16) which extends through the opening 246 and supports 70 a pair of rollers 248 and 249. Said pivot member 242 may have substantially the same construction as that of the pivot member 34 (FIGURE 7).

The support plate 239 is removably held upon the brackets 231 and 232 by means such as the nuts and bolts 75

252. In this particular embodiment, the support plate 239 is shown in a substantially horizontal position and the pivot pin 247 is in a substantially vertical position. However, by a modest adjustment in the elevation of the support bracket 232, for example, and the mounting of the pivot member 242 upon the door 253, the upper hinge 230 can be mounted in a slightly sloping position, as disclosed hereinabove with respect to the upper hinge 10.

10 The operation of the upper hinge 230 may be and preferably is substantially the same as discussed hereinabove with respect to the upper hinge 10, except for the slight variation produced by providing a horizontal support plate 239, the effect of which is covered in substance by the operation described hereinabove with respect to the upper hinge 110 (FIGURE 3).

15 As shown in FIGURE 17, a hinge 260 which somewhat resembles the hinge 110 (FIGURE 9) may be mounted upon the lower portion of a door 261 to effect substantially the same purposes achieved by mounting said hinge 110 at the top of the door 111. More specifically, the hinge 260 includes a support bracket 262 which is substantially rectangular in shape and is received into a notch 263 in the lower corner of the door 261 adjacent the side jamb 264. Said bracket 262 includes a 20 pair of substantially parallel flanges 266 and 267 which are spaced from but extend toward each other, preferably substantially adjacent the lower edge of the door 261. A support plate 268, which may be substantially identical with the support plate 63 (FIGURE 3), has its opposite 25 ends disposed beneath and held against the flanges 266 and 267 by means such as the bolts and nuts 269.

20 Said support plate 268 (FIGURE 17) has a downwardly facing, transverse groove 272 into which the rollers, which are mounted on opposite sides of the pivot pin 273, are receivable. One of these rollers is shown at 274 in FIGURE 17. Said pivot pin 273 extends through an appropriate opening through the groove 272 in substantially the same manner as discussed above with respect to the hinge 110 (FIGURE 9). However, said pivot pin 273 is, in this particular embodiment, supported at its lower end upon the horizontal flange 276 of the L-shaped bracket 277, the other flange of which is secured to side jamb 264 by screws 278.

25 The operation of hinge 260, is in general, similar to the operation of the hinge 110. Moreover, said hinge 260 can be made so that the support plate 268 is sloped downwardly away from the side jamb 264 to better accommodate same to a hinge axis which diverges upwardly with respect to the side jamb 264, in a manner previously discussed in detail.

30 Although particular preferred embodiments of the invention have been disclosed above for illustrative purposes, it will be understood that variations or modifications of such disclosure, which come within the scope of the appended claims, are fully contemplated.

35 50 What is claimed is:

1. A hinge structure for supporting a door adjacent an opening in a wall structure for movement around a hinge axis parallel with the plane of said door, said axis being at a small acute angle to the vertical centerline of the door, comprising:

35 40 45 50 55 a support mechanism connected between substantially horizontal and adjacent edge portions of said door and said wall structure adjacent said opening, said support mechanism comprising pin means substantially parallel and substantially concentric with said axis, a pair of support elements mounted upon substantially opposite sides of said pin means, and a support plate substantially perpendicular to said pin means, said plate having a pin opening through which said pin means extends and substantially V-shaped recess means into which said support elements are substantially simultaneously receivable on substantially opposite sides of said pin opening, whereby said door is substantially supported by said support mecha-

nism for pivotal movement around said axis, said door being urged by gravity into a position wherein both support elements are disposed in said recess means and thereby opposite pivotal movement of said door; and

guide means connected between other adjacent edge portions of said door and said wall structure adjacent said opening and remote from said support mechanism, said guide means being located along said axis to guide the pivotal movement of said other adjacent portion of said door.

2. A hinge structure according to claim 1 wherein the lengthwise axis of said pin means is parallel with the vertical centerline of the door and, accordingly, at a small acute angle to said hinge axis; and

wherein said support plate is perpendicular to said lengthwise axis of said pin and, accordingly, at a large acute angle to said hinge axis.

3. A hinge structure according to claim 1 wherein said pin means is secured to said wall structure and its lengthwise axis is parallel with the vertical centerline of the door and, accordingly, is at a small acute angle to said hinge axis; and

wherein said support plate is secured to said door and is perpendicular to said pin means, said recess means opening downwardly.

4. A hinge structure according to claim 1 wherein said guide means includes a guide pin secured to said wall structure near the lower end of said door and extending upwardly parallel with the vertical centerline of the door, and a guide member on said door defining an opening into which said guide pin is loosely and slideably received.

5. A hinge structure according to claim 1 wherein said guide means is located near the top of said door and the support mechanism is located near the bottom of said door, said pin means being mounted upon said wall structure and said support plate being mounted upon said door so that the lengthwise axis of said pin means is parallel with the vertical centerline of the door, perpendicular to said support plate and at a small acute angle to the hinge axis, said recess means opening downwardly.

6. A hinge structure according to claim 1 wherein said pin means is mounted upon said wall structure, said support plate is mounted upon said door and said recess means opens downwardly; and

including cover means mounted upon said door and covering a substantial portion of said support mechanism.

7. A hinge structure according to claim 1 wherein said pin means is secured to said wall structure and is parallel with said centerline of said door; and

wherein said support mechanism includes bracket means secured to the upper edge of said door, said support plate being adjustably secured to said bracket means and perpendicular to the lengthwise extent of said pin means, said recess means opening downwardly.

8. A hinge structure according to claim 1 wherein said support elements comprise a pair of rollers and shaft means extending from opposite sides of said pin means and supporting said rollers for rotation around substantially horizontal axes substantially perpendicular to said plane of said door when said door is in said position.

9. The structure of claim 1 wherein said pin means and part of said guide means are rigidly secured to said door near one upright edge thereof;

wherein said support plate and another part of said guide means are secured to said wall structure; and wherein said recess means opens upwardly.

10. The structure of claim 1 wherein said pin means is rigidly secured to said wall structure;

wherein said support plate and part of said pivot means are rigidly secured to said door; and wherein said recess means opens downwardly.

11. The structure of claim 1 including a second hinge

70
75

structure like the first-mentioned hinge structure supporting a second door adjacent said opening in said wall structure for movement around a hinge axis disposed within a substantially vertical plane containing the first-mentioned hinge axes, said first and second axis converging upwardly toward each other; and

wherein the adjacent edges of said doors have resiliently flexible sealing elements thereon engageable substantially throughout their lengths with each other when said doors are in substantially parallel positions.

12. A hinge structure for supporting a door upon a wall structure adjacent an opening therein for movement around a hinge axis parallel with the plane of said door, said axis being near one upright edge of said door and diverging upwardly at a relatively small, acute angle to a vertical line adjacent said edge of said door, comprising:

a support member securable to said wall structure adjacent said opening, said member including an upright side element and upper and lower end elements extending from said side element at spaced points thereon and in substantially the same direction therefrom;

pivot pin means secured to the upper end element and extending downwardly therefrom;

a pair of rollers supported upon substantially opposite sides of said pivot pin means for rotation around substantially horizontal axes substantially perpendicular to the plane defined by said elements;

a mounting plate secured to the door and having a central opening through which said pivot pin means is loosely received, said mounting plate having downwardly opening, substantially V-shaped groove means on opposite sides of said opening and substantially perpendicular to said door, said rollers being disposed within said groove means when said door is substantially disposed within said plane; and

pivot means connected between the lower end element and said door to guide the movement of said door around said axis, whereby said door is pivotally movable in both horizontal directions away from said position substantially within said plane, wherein said door is urged by gravity.

13. A hinge structure for supporting a door upon a wall structure adjacent an opening therein for movement around a hinge axis parallel with the plane of said door, said axis being near one upright edge of said door and diverging upwardly at a relatively small, acute angle to a vertical line adjacent said edge of said door, comprising:

pivot pin means rigidly secured to said wall structure near the upper edge of said opening and near a substantially vertical edge of said opening, said pivot pin extending downwardly substantially vertically;

a pair of similar rollers and means supporting same upon substantially opposite sides of the pivot pin means for rotation around substantially horizontal axes substantially perpendicular to the plane defined by said edges of said opening;

a mounting plate secured to the door adjacent an upper edge portion thereof and near said upright edge thereof, said mounting plate being substantially perpendicular to said pivot pin means and having a central opening through which said pivot pin means is loosely received and having a downwardly opening, substantially V-shaped groove extending across said opening and substantially perpendicularly to the plane of said door, said rollers being disposed within said groove when the door is substantially disposed within said plane; and

lower pivot means connected between the lower edge portion of said door and said wall structure to guide the movement of said door around said hinge axis, the hinge axis extending through said pivot pin means and said pivot means, whereby said door is pivotally supported for substantially horizontal move-

ment in both directions away from a position substantially within said plane, wherein said door is urged by gravity.

14. A hinge structure according to claim 13 wherein the axes of said pivot pin means and said pivot means are parallel and spaced transversely from each other so that they are both at a small acute angle to said hinge axis, whereby movement of said door away from said position within said plane causes said door to be supported primarily by engagement of one of said rollers 10 with said support plate.
